MESNE ASSIGNMENTS, TO THE ELWELL-PARKER ELECTRIC COMPANY, OF CLEVE-
LAND, OHIO, A CORPORATION OF OHIO.

DRIVING-GEARING.

1,120,355.

Specification of Letters Patent.

Patented Dec. 8, 1914.

Application filed July 22, 1912. Serial No. 710,889.

To all whom it may concern:

Be it known that we, CHARLES E. F. AHLM and CLYDE E. COCHRAN, citizens of the United States, residing at Cleveland, in the county of Cuyahoga and State of Ohio, have invented a certain new and useful Improvement in Driving-Gearing, of which the following is a full, clear, and exact description, reference being had to the accompanying drawings.

This invention relates to that class of driving gearing wherein there are two connected gears which, in addition to their respective rotations, partake of motion about other axes. An illustration of such class of gearing may be found, for example, in those automobiles where the wheels that steer are also driven, such wheels having a gear with which meshes a pinion having a universal 20 swinging action, so that it may be rotated by a shaft in fixed bearings and still drive the gear irrespective of the position of the wheel. Such system of gearing is shown, described and claimed in Patent No. 875,892, granted January 7, 1908, to Tracy V. Buckwalter. We have found that, with this type of driving gearing, there is a considerable wear between the pinion and the gear; for, as the gear swings back and forth in steering the vehicle, such movement causes first one corner and then the other of the pinion to become worn.

The object of our invention is to provide suitable protective means by which the wear is avoided and the pinion caused to run true with reference to the gear, irrespective of the position of the latter. We have accomplished this by providing a shroud carried centrally by one of the gear members and occupying a groove in the other. This shroud maintains the teeth of the pinion and gear in proper parallel relation without interfering with the swinging or tipping of each member. We have found it preferable, particularly when the gear is an internal one, to carry the shroud in the gear and to form the cooperating groove in the pinion, but it is to be understood that we are not limited to mounting the shroud in the gear in preference to the pinion.

In the drawings, which clearly illustrate our invention, Figure 1 is a front elevation, partly sectional of an automobile construction having steering wheels with internal

gears driven by universally mounted pinions, the gears and pinions being equipped with our invention; Fig. 2 is a detail, being a vertical section through the pinion and operating gear; Fig. 3 is a side elevation, partly sectional, of a portion of the driven gear and the driving pinion, the plane of the section being offset so that the gear is shown in elevation, while the pinion is in central section.

As shown in Fig. 1, 10 represents a suitable axle frame, which carries the pivoted axles and their wheels and carries also the driving gearing therefor. This frame is suitably connected by means not shown with depending members 11 from a platform or chassis frame 12. The vehicle wheels are designated 15. Their hubs 16 are mounted on short axle sections 17 which project from a swinging block 18 journaled vertically in bearings 13 and 14 in the frame 10. A suitable steering knuckle on the block 18 and connecting rod 19 furnish means for turning the wheel to steer the vehicle, as will be well understood.

To drive the wheel, we mount therein an internal gear 20, with which meshes a pinion 21 which is suitably mounted on the end of one of the drive shafts 22 or 23. These shafts stand in alinement, the inner ends being connected by suitable differential gearing within the casing 24. This gearing is driven by suitable means, as, for example, by the motor 25. The shaft sections 22 and 23 are suitably journaled in housings 26 carried by the upper portion of the main frame 10.

The construction so far described should be taken as illustrative of any suitable embodiment of a driven gear and a meshing driving gear which are designed to partake of a swinging movement about other axes than those of rotation. In order to allow this swinging movement to take place, the pinion 21 is mounted by a universal joint on the shaft 22 or 23. The universal joint connection is effected by an intermediate block 30 which is pivoted at diametrically opposite points 31 to the pinion proper, while, at two other diametrically opposite points, which are ninety degrees from the points 31, this block is connected with the shaft 22 or 23. These connections are conveniently accomplished by forming trunnions on the

block 30 which fit into blocks 34 held in recesses in the inner face of the pinion. The block is conveniently connected with the shaft by the pin 35, this pin passing through 6 the square end of the shaft and being itself held thereto by the tapered pin 36, shown in Fig. 3.

From the above construction, it will be seen that when the shaft 22 or 23 is rotated, 10 the pinion rotated thereby drives the gear 20, and the connected wheel 15, and such driving does not interfere with the steering movement of the wheel about the axis of the journals 13 and 14, which is in line with the 15 center of the pinion. Such swinging, however, has a tendency to cause the teeth of the gear to bind on the teeth of the pinion. That is to say, when the steering wheel turns 20 in one direction, the pinion teeth on one corner thereof tend to grind on the gear teeth, thus wearing both the gear teeth and the pinion teeth; then, when the steering wheel swings in the opposite direction, the wear comes on the other corner of the pinion 25 teeth. The result is that both the pinion and gear become undesirably worn.

We have found that we can prevent the undesirable wear without interfering with the efficiency of the drive, or the ease of 30 steering, by mounting a shroud centrally in the driven gear and allowing it to constantly 35 occupy a peripheral groove in the pinion. In each of the views the shroud is designated 40. It consists of a ring, split at 41, (Fig. 3) and forced into a groove made in the gear in the central plane thereof. When 45 in position, the shroud is held in place, for example, by pins 43 and 44 passing transversely through the teeth of the gear and 50 through the shroud near its end. The inner peripheral edge of the shroud is preferably mounted.

45 indicates the central peripheral groove which is occupied by the shroud. The action of the shroud in the groove, while not introducing additional friction of material amount, does maintain the pinion teeth parallel with the engaged teeth of the driven gear. As will be seen from Fig. 3, the 55 shroud always occupies several teeth of the pinion, so that the desired alinement is necessarily maintained.

Having thus described our invention, what we claim is:

55 1. The combination of a wheel mounted to be swung about an axis transversely to its axis of rotation, an internal gear on said wheel, a pinion meshing with said gear, a shaft, a universal joint connection between

the pinion and shaft, and a shroud carried 60 by one of said meshing members and occupying a groove in the other to prevent the pinion digging into the gear.

2. The combination of a wheel mounted to rotate and to be swung on an axis at right 65 angles to its axis of rotation, a gear carried by said wheel, a pinion meshing with said gear, a driving shaft, a universal joint between the pinion and driving shaft, and a shroud located in intermediate position on 70 one of the meshing members and occupying a corresponding groove in the other member.

3. The combination of a wheel, means for swinging it about an axis at right angles to its axis of rotation, a gear on said wheel, a 75 shroud carried by said gear and projecting beyond its pitch line, and a universally mounted pinion adapted to mesh with the teeth of the gear and having a peripheral groove occupied by the shroud. 80

4. The combination of a driven gear, a driving pinion therefor, a driving shaft for the pinion, a universal joint connection between the pinion and its shaft, and a positioning device for the gear and pinion comprising a shroud carried by one of such 85 members and occupying a groove of the other member which is as deep as the teeth thereon, said shroud extending substantially to the base of said groove. 90

5. The combination of a wheel, an internal gear carried thereby, a shroud seated therein and consisting of a split ring held in a groove in the face of the gear, means for swinging said wheel about an axis at right 95 angles to its axis of rotation, and a universally mounted pinion co-operating with the gear and having a peripheral groove adapted to coact with said shroud.

6. The combination of an internal gear, a 100 shroud seated in a groove in the middle of the face of the gear, said shroud consisting of a split ring projecting toward the axis of the gear beyond the face of the teeth, and a universally mounted pinion co-operating 105 with the gear and having a peripheral groove in the middle of its face, said groove extending inwardly as far as the base line of the teeth of the pinion.

In testimony whereof, we hereunto affix 110 our signatures in the presence of two witnesses.

CHARLES E. F. AHLIM.
CLYDE E. COCHRAN.
